(57) **CLAIM**

The ornamental design for a dispenser for miniature batteries or other objects, as shown and described.

DESCRIPTION

FIG. 1 is a front perspective view of the dispenser for miniature batteries or other objects;

FIG. 2 is a top elevational view of the dispenser for miniature batteries or other objects;

FIG. 3 is a bottom elevational view of the dispenser for miniature batteries or other objects;

FIG. 4 is the right side elevational view of the dispenser for miniature batteries or other objects; the left side elevational view (not shown) is a mirror image of the right side elevational view;

FIG. 5 is a front elevational view of the dispenser for miniature batteries or other objects; and,

FIG. 6 is a rear elevational view of the dispenser for miniature batteries or other objects.

The broken lines showing of the environment are for illustrative purposes only and form no part of the claimed design.
